UNITED STATES PATENT OFFICE.

CHARLES LAMOREAUX, OF CHARLESTON, WEST VIRGINIA.

VALVE.

1,041,636.

Specification of Letters Patent.

Patented Oct. 15, 1912.

Application filed July 15, 1912. Serial No. 709,488.

To all whom it may concern:

Be it known that I, CHARLES LAMOREAUX, a citizen of the United States of America, residing at Charleston, in the county of 5 Kanawha and State of West Virginia, have invented certain new and useful Improvements in Valves, of which the following is a specification, reference being had therein to the accompanying drawing.

10 This invention relates to valves, particularly designed for use in the oil well fields for closing the upper end of a well casing or tube whereby gas or oil cannot escape from the casing or tube until proper connections have been made for storing the liberated product of nature.

The primary object of my invention is to provide a valve body that can be easily and quickly mounted upon the upper end of the 20 casing or tube for controlling the outlet of said casing or tube, the valve body inclosing flap valves that can be simultaneously operated and locked in adjusted position.

A further object of this invention is to 25 provide a valve of the above type that is non-leakable, consisting of comparatively few parts inexpensive to manufacture and highly efficient for the purposes for which it is intended.

30 With the above and other objects in view the invention resides in the novel construction, combination and arrangement of parts to be hereinafter specifically described and then claimed.

35 Reference will now be had to the drawing, wherein:—

Figure 1 is a side elevation of the valve, Fig. 2 is a vertical sectional view of the same, Fig. 3 is a longitudinal sectional view 40 of the valve, Fig. 4 is a horizontal sectional view of the same, and Fig. 5 is a perspective view of a detached flap valve.

Further describing my invention with reference to the drawing wherein like numerals 45 denote corresponding parts 1 denotes a hollow valve body oval in elevation and circular in plan, said valve body having a depending central cylindrical coupling member 2 whereby the valve body can be mounted 50 upon a tube or casing. The top of the valve body has a central cylindrical outlet sleeve 3 provided with an annular interior groove 4 for packing 5. A closure 6 can be placed upon the packing 5 and secured thereto by 55 set screws 7, whereby the outlet sleeve 3 will be closed. The edges of the closure 6

are beveled, as at 8 and these edges are engaged by the screws 7 whereby the closure will be forced against the packing to form a non-leakable connection. 60

Oppositely disposed sides of the valve body 1 have ports 9 with the walls thereof screw threaded to receive screw plugs 10. The ports 9 permit of the contents of the valve body being drawn off. 65

Oppositely disposed sides of the valve body 1 are provided with inwardly projecting bosses 11 and 12 the former providing stuffing boxes 13 to accommodate packing 14 and glands 15. Extending through the 70 glands 15 and the bosses 11 and 12 are rock shafts 16 that are arranged in parallelism with the outer ends thereof projecting from the glands 15 and having rectangular shanks 17. 75

Mounted upon the rock shafts 16 are the barrels 18 of semicylindrical flap valves 19, said valves having the edges thereof beveled, as at 20 to form a positive connection when said valves are closed and engage the inner 30 end of the outlet sleeve 3.

Mounted upon the outer ends of the rock shafts 16 are sectors gears 21 that mesh with each other whereby said rock shafts can be rotated in unison one-quarter of a revolution. 85

Detachably mounted upon the shanks 17 of the shafts 16 is a bar 22 and said shanks are provided with openings to accommodate locks or seals 23 employed to prevent the removal of the bar 22 by unauthorized persons. 90 The bar 22 can be used upon one of the shafts as a lever for rocking both of said shafts, either to open or close the flap valves 19.

It is thought that the operation and utility of a valve in accordance with this invention will be apparent without further description and while in the drawing there is illustrated a preferred embodiment of the invention, it is to be understood that the structural elements are susceptible to such 100 changes, as in the size, shape and manner of assemblage, as fall within the scope of the appended claims.

What I claim is:—

1. A valve of the type described comprising a hollow body having a depending coupling member, an outlet sleeve in communication with the top of the body, a closure detachably mounted in the outer end of said sleeve, rock shafts supported by the opposite 110 sides of said body, flap valves mounted upon said shafts and co-operating in closing the

- inner end of said outlet sleeve, and means carried by said shafts whereby said shafts can be rocked in unison to open and close said valves.
- 5 2. A valve of the type described comprising a hollow body having a depending coupling member, an outlet sleeve in communication with the top of the body, a closure detachably mounted in the outer end of said 10 sleeve, rock shafts supported by the opposite sides of said body, flap valves mounted upon said shafts and coöperating in closing the inner end of said outer sleeve, means car-

ried by said shafts whereby said shafts can be rocked in unison to open and close said 15 valves, said means including sector gears, and a bar detachably mounted upon the ends of said shafts adjacent to said sector gears.

In testimony whereof I affix my signature 20 in the presence of two witnesses.

CHARLES LAMOREAUX.
